UNITED STATES PATENT OFFICE.

JULES E. ROINÉ, OF NEW YORK, N. Y., ASSIGNOR TO THE WESTERN CLOCK MANUFACTURING COMPANY, OF LA SALLE, ILLINOIS, A CORPORATION OF ILLINOIS.

DESIGN FOR A CLOCK-FRAME.

No. 38,261.

Specification for Design.

Patented Oct. 2, 1906.

Application filed August 18, 1906. Serial No. 331,210. Term of patent 7 years.

To all whom it may concern:

Be it known that I, JULES E. ROINÉ, a citizen of France, residing at New York, in the county of New York and State of New York, have invented a new, original, and ornamental Design for a Clock-Frame, of which the following is a specification, reference being had to the accompanying drawings, which show my design.

Figure 1 is a front view, and Fig. 2 a side view, thereof.

What I claim is—

The ornamental design for a clock-frame as shown.

JULES E. ROINÉ.
